United States Patent Office.

AUGUSTUS THAYER, OF ALBANY, NEW YORK.

Letters Patent No. 79,027; dated June 16, 1868.

IMPROVED IMPLEMENT.

The Schedule referred to in these Letters Patent and making part of the same.

TO ALL WHOM IT MAY CONCERN:

Be it known that I, AUGUSTUS THAYER, of Albany, in the county of Albany, and State of New York, have invented a new and useful Combination-Tool; and I do hereby declare that the following is a full, clear, and exact description thereof, which will enable others skilled in the art to make and use the same, reference being had to the accompanying drawings, forming part of this specification, in which—

Figure 1 is a side view of my invention.

Figures 2 and 3, edge views of the same.

Figure 4, a side view of the same in an open state.

Figure 5, a section of a portion of the same, taken in the line $z z$, fig. 4.

Similar letters of reference indicate like parts.

This invention relates to a new and useful combination of various tools, as hereinafter fully shown and described, whereby a very useful implement is obtained for household use, and one which may be used in each of its different capacities with perfect facility.

A A' represent two handles, which cross each other, and are connected by a rivet or fulcrum, α , like a pair of shears. One of these handles, A, has a cylindrical bar, B, on its outer end, at right angles thereto, and at the under side of the bar B, at one end thereof, the concaves $b b'$ are made, said concaves being portions of circles, b being larger than b' , as shown clearly in fig. 4.

The concaves are corrugated or toothed, and the end of the handle A is curved or bent to form a right-angular projection, C, which works under the concave $b b'$, and forms the centre part of the portion of the bar B in which said concaves are made. This projection, C, has two-toothed surfaces, $c c'$, at one side of it, c being a concave, and c' being a convex surface, as shown in fig. 4, and at its opposite side there is a toothed convex surface, d , shown in fig. 1.

These concave surfaces form a pipe-tongs, which may be used for turning gas-burners, attaching them to or detaching them from their burners, and also for turning any cylindrical article; while the concave and convex surfaces may be used as pincers, to grasp hold of any article.

The under side of the bar B, at the opposite side of the handle A, also has a concave, e , made in it, and a corresponding concave, f , is made in the handle A' below the fulcrum or rivet α . These concaves $e f$ may be used for turning larger pipes or tubes. These can be turned with the other concaves, and they may also be used for grasping and turning other articles.

At the end of the projection C of the handle A, there is an eye, g' , having an internal screw-thread, in which a screw of a serrated or notched head, D, passes. The screw passes through the centre of this head, and the latter is provided with notches h , of different sizes, so that either of said notches may be brought in line with the outer edge of the bar B at its centre, as may be desired.

This notched head is designed for picking up tacks by the head, for the purpose of tacking down carpets or other floor-cloths; the tacks being picked up by the head by the implement as they may lie promiscuously in a box or on a floor or carpet, and while thus grasped between the head D and the end of bar B, as shown in fig. 1, they may be stuck in the carpet, and the latter stretched to its place, and the tacks driven into the floor, without any special handling.

The different-sized notches admit of different-sized tacks being grasped with facility, and the head D may be secured in any desired position by having the screw αx , at the part adjoining its head, of polygonal form, and a polygonal hole in the head D, (see fig. 5.) If necessary or desired, the inner surface of the head D may be slightly corrugated or roughened, in order to insure the heads of the tacks being firmly grasped.

In the bar D there are inserted cutters $i i$, designed to sharpen knives and other cutlery.

This device for sharpening cutlery forms the subject of a separate application, and is merely alluded to here as one of the features included in the combination of the several parts.

The handle A has two or more notches, j , made in one edge above its fulcrum, α , to serve as wire-cutters,

a hole, *k*, being made through the handle *A'* for the insertion of the wire. A notch, *l*, may also be made in the edge of the handle *A*, to serve as a wire-cutter in connection with one of the notches *j*. Holes *m* are also made through both handles, *A A'*, to serve as cutters. These holes and notches may be made of different capacities, to suit wire of different sizes.

At the inner surface of each handle *A A'*, there are projections, *n*, to serve as holders, to prevent the escape of substances placed between them. This feature of the device is designed more especially for cracking nuts.

At the angle of the handles *A A'*, below the fulcrum *a*, there is made in the inner surface of each handle a transverse groove, *o*. This feature is designed more especially to serve as pincers for holding a sewing-machine needle while being set. In one edge of the handle *A*, near its outer end, there are made transverse slots *p*, to serve as a saw-set, and the outer end of the other handle *A'* is formed with a claw, *q*, for the purpose of drawing tacks and small nails. At the extreme end of the handle *A* there is a screw-driver, *h*.

I would remark that, if desired, the head *D* may be fixed, and answer equally well for ordinary purposes, or where tacks, not varying materially in size, are only used.

Having thus described my invention, I claim as new, and desire to secure by Letters Patent—

The implement, consisting of the parts *A A'*, having the head *B*, tack-holder *D*, roughened surfaces *b b'*, *c c'*, *d*, *e*, *f*, notches *j l*, holes *k m*, cutters *i i*, grooves *o*, projections *n*, saw-set *p*, screw-driver *h*, and claw *g*, all constructed and arranged to operate, substantially as and for the purposes herein shown and described.

AUGUSTUS THAYER.
